UNITED STATES PATENT OFFICE.

WILLIAM G. CHIPLEY, OF ATLANTA, GEORGIA.

CROSS-TIE.

1,030,230.

Specification of Letters Patent. Patented June 18, 1912.

Application filed December 18, 1911. Serial No. 666,534.

To all whom it may concern:

Be it known that I, WILLIAM G. CHIPLEY, a citizen of the United States, residing at Atlanta, in the county of Fulton and State of Georgia, have invented certain new and useful Improvements in Cross-Ties; and I do hereby declare the following to be a full, clear, and exact description of the invention, such as will enable others skilled in the art to which it appertains to make and use the same.

This invention relates to cross-ties and it consists in the novel construction herein-after described and claimed.

In the accompanying drawings forming part of this application Figure 1 is a view of a portion of a tie in vertical longitudinal section and showing the rail and securing devices in transverse section. Fig. 2 is a top plan view partially in section of the construction shown in Fig. 1. Fig. 3 is a side elevation of a reinforcing channel member. Fig. 4 is a bottom plan view thereof. Fig. 5 is an end view. Fig. 6 is a section on the line 6—6 of Fig. 4. Fig. 7 is a view of one of the securing blocks for insertion in the recess in the tie and adjoining the rail. Fig. 8 shows a rail in vertical transverse section with the securing devices in position, these devices being mounted above a lower plate resting in the recess in the tie. Fig. 9 shows another form of wedge block.

In carrying out my invention I make use of a tie of concrete or other plastic material indicated by 10 and shown in Fig. 1 where one end of the tie appears with one of the rails suitably secured. The tie is reinforced longitudinally by a channel member 15 shown in detail in Figs. 3 to 6 inclusive and in dotted lines in Fig. 1. One or more of these channel members can be employed as may be found desirable. The tie is recessed transversely as indicated at 16, the recess being wider at one end forming a wedge-shaped cut away portion of substantially the configuration illustrated in Fig. 2. Within the recess the rail is mounted at a suitable distance above the base and is wedged into position by means of blocks 17 and 18 having the form shown in Fig. 7. These blocks are provided with grooves 19 extending the full length and located near the base leaving a lower horizontal member 20 which projects under the base of the rail. The edge of member 20 is beveled in order that the blocks when in position may over-

lap and form a complete and substantial support for the rail. The upper surface of the block is beveled as indicated at 21 and is also beveled at 22, the side last mentioned engaging the under cut wall 23 of the recess formed in the tie. The blocks 17 and 18 are preferably somewhat less than the full transverse measure of the tie and may be secured after being placed in position by any suitable means. Ordinarily the wedging action of the blocks is sufficient. The blocks engage the flange of the rail and the web, and extend to the lower portion of the head.

In Fig. 1, I have shown the central portion of the tie 25 as being reduced in size, whereby heavy end portions are formed, as compared with the central portion. These end portions constitute pedestals for the rails. In Fig. 8 the lower portion of the tie 75 is cut away at 26 and it is obvious that any suitable mold might be employed, the exact form of the tie being immaterial.

Referring more particularly to the reinforcing device, it will be obvious that this 80 device consists of a channel member 15 having its flared edges projecting upwardly and being cut away where the rails are engaged. In forming these cut away portions, I may cut out a portion 30 having beveled edges 85 31, said portion 30 being turned down as shown in Fig. 3, in order to stiffen the channel member at the portion where it would otherwise be weak. These turned down portions 30 tend to reinforce the concrete and the concrete in turn reinforces the weakened portions of the channel member. In Fig. 4 a bottom plan view of the channel member is shown and it will be observed that the flared portions or sides of the channel 95 are connected transversely at 32, 33 and 34. The length of these connecting portions may of course be varied but it is desirable that there be sufficient metal in the central portion 33 to hold the tie together 100 in the event of the fracture of the concrete body portion. Portions of the channel member may be provided with perforations, as shown at 35, the edges of these perforations being flared for engaging and reinforcing the concrete.

In the form shown in Fig. 8 a plate 40 extends beneath the rail and preferably the full width of the transverse recess of the tie and under these circumstances the blocks 110 41 and 42 are formed somewhat differently, the grooved portions being unnecessary.

In order to provide blocks for use on curves where the rail would not contact with a straight edge for any considerable distance the blocks may be curved slightly as shown 5 in Fig. 9.

The blocks or wedges may be of metal, wood, wood-pulp, or composition. If of metal, they may be inserted with a paper sheathing, shown at 45 in Fig. 8, this sheathing being used on the sides or the sides and bottom.

If desired, two forms of lugs or ears may be used on a single channel member, as in Fig. 1, where the devices 30' are turned outwardly at 30''. A portion of member 15 is turned over at 15', in order to stiffen the structure.

What I claim is:

1. In a device of the class described, a tie 20 provided with a transverse recess, a reinforcing member extending longitudinally of the tie and cut away to afford an opening conforming to the lower portion of the recess, and rail engaging devices for insertion 25 within the recess on opposite sides of the rail, said devices each cushioning the head and base of the rail.

2. In a device of the class described, a tie 30 provided with a channel-shaped reinforcing member the flanged sides of which project toward the upper side of the tie, said flanged sides being cut away, the tie being provided with a transverse recess, the walls of the 35 lower portion of which coincide with the cut away portion of the channel member, and means for insertion within the recess on opposite sides of the rail for engaging the reinforcing member, cushioning the head of the rail.

3. In a device of the class described, a tie 40 provided with a transverse recess and a reinforcing member having a cut away portion conforming in part to the configuration of the recess, and means for insertion within 45 the recess and engaging the flange and web of the rail and the said reinforcing member and for cushioning the head of the rail.

4. In a device of the class described, a tie 50 provided with a reinforcing member and a transverse recess, and means for insertion within the recess and engaging the reinforce-

ing member, the sides of the recess and adapted to engage a rail received within said recess and to cushion and partially support the head thereof.

5. In a device of the class described, a tie 55 provided with a reinforcing member and a transverse recess, and wedge shaped devices for insertion within the recess and engaging the reinforcing member, the sides of the recess, and adapted to engage a rail received within said recess and to cushion and partially support the head thereof.

6. In a device of the class described, a tie 60 provided with a recess having side walls inclined in two directions, a reinforcing member for the tie having a cut away portion, said cut away portion coinciding in part with the walls of the recess, and means for insertion in the recess adapted to engage a 65 rail received therein, said means constituting a direct connection between the lower portion of the head of the rail and the reinforcing member.

7. In a device of the class described, a tie 70 provided with a transverse recess, a plate 75 located therein and adapted to receive and support a rail, and wedge shaped devices for insertion in the recess and engaging opposite portions of the rail, said devices constituting a direct connection between the lower portion of the head of the rail, and the reinforcing member.

8. In a device of the class described, a tie 80 provided with a transverse recess, a reinforcing member within the tie and provided with a cut away portion adjacent to the sides of the recess, a plate located horizontally within the recess and adapted to receive and support a rail, and devices for engaging the 85 walls of the recess, the reinforcing member and portions of the rail for securing the latter, said devices partially supporting the head of the rail and constituting cushioning members between the head and plate.

In testimony whereof I affix my signature in presence of two witnesses.

WILLIAM G. CHIPLEY.
